UNITED STATES PATENT OFFICE

96,374

DESIGN FOR A STANDARD FOR A CAN- DELABRUM OR OTHER ARTICLE

Simon W. Farber, Brooklyn, N. Y.

Application February 15, 1935, Serial No. 55,444

Term of patent 14 years

To all whom it may concern:

Be it known that I, Simon W. Farber, a citizen of the United States, residing at 44 Marlboro Road, Brooklyn, in the county of Kings and State of New York, have invented a new, original, and ornamental Design for a Standard for a Candelabrum or Other Article, of which the following is a specification, reference being had to the accompanying drawing, forming part thereof.

Figure 1 is a front view, and Figure 2 is a view in perspective of a Standard for a candelabrum or other article, showing my new design.

The dominant characteristics of the design are the serpentine central member and the curved arms extending from the convex portions thereof. The number of arms is not an important feature of the design.

I claim:

The ornamental design for a standard for a candelabrum or other article, substantially as shown and described.

SIMON W. FARBER.
